UNITED STATES PATENT OFFICE.

DONALD A. MCKENZIE, OF SWARTHMORE, PENNSYLVANIA.

SLUB CUTTER.

Application filed November 11, 1924. Serial No. 749,192.

My invention relates to slub cutters, and provides among other features of structural advantage, a freely swinging blade of economical construction, means for readily detaching the same from its carrier to facilitate cleaning, substitution of the knife, etc., without disturbing the adjustment of the cutter mechanism as a whole, and means for readily adjusting the parts not only with respect to each other, but also with respect to the support.

Referring to the accompanying drawings—

Fig. 1 is a partial side elevation of an installation in which my improved slub cutter is shown in one form;

Fig. 2 is a broken side elevation of the slub cutter viewed at right angles to Fig. 1;

Fig. 3 is a section on the line 3—3, Fig. 2; and

Fig. 4 is a side elevation of the cutter blade detached.

To illustrate the invention I have shown in Fig. 1 a spool 5 upon which the thread 6 is wound from the reel 7. Between the reel and spool is arranged the slub cutter to which my invention particularly relates.

The slub cutter, as shown, comprises a clamp head 8 slotted at one end to form a pair of jaws, between which is received a thread guide bar 9 held in adjusted position by the clamping screw 10. While any suitable means may be provided for mounting the clamp head upon an appropriate support, I have shown for this purpose a rod 11 passing transversely through the thread guide 9, to which it is secured by set screw 12. Its opposite end extends to a frame member of the spooling machine, as conventionally indicated at 13.

Cooperating with the thread guide 9 is a deflecting finger 14, by which the angle at which the thread 6 passes to the guide 9 may be varied. The deflecting finger 14 is shown in the form of a wire rod fastened at one end in a collar 15 rotatably mounted on the guide 9 and held in adjusted position thereon by means of the set screw 16.

The blade carrier 17 which extends parallel to the thread guide 9, is clamped by screw 18 between jaws formed at the opposite end of the clamp head 8. While the carrier may be formed in various ways, I have used for this purpose a solid bar provided at its free end with a longitudinally extending segmental slot 19 in which is re-

ceived the back of the cutter blade 20. To hold the latter in position in the slot, the ends of the blade are notched at 21 to receive the legs 22 and 23 of a cooperating spring catch 24. The anchor leg 22 of the catch passes through the carrier bar at a point intersecting the segmental slot 19, while the leg 23 of the catch is freely seated in a transverse notch 25 in the end of the carrier bar 17. The spacing and location of the legs 22 and 23 of the spring catch 24 is such that while they engage in the notches 21 in the blade, and thus prevent its escape from the carrier, they are so loosely engaged that they do not interfere with its freely swinging transverse movement in the segmental slot 19. They are of course so positioned that the blade edge is parallel to the axis of the thread guide bar 9.

A side recess 26 may be formed in the blade carrier to accommodate the loop 27 and adjacent portions of the spring latch.

In properly adjusted position for operation, the cutting edge 28 of the blade 20 lies parallel and adjacent to the thread guide 9, but sufficiently spaced therefrom to permit the thread to pass freely. The blade is positively supported in this position by one side *a* of the V-slot 19 in the carrier bar, which for this purpose is rotated until the side *a* of the slot picks up the freely hung blade, and deflects it slightly from the vertical, in which adjusted position the carrier is clamped fast. The position of the blade edge with respect to the thread guide 9 is thus positively located while leaving the blade free to swing across the slot 19 toward the guide bar 9 to engage and cut the thread. The position of the blade indicated is that at which it is most sensitively responsive, but it will be understood that on varying the angular position of the clamp head 8 on the thread guide 9, followed by appropriate modification of the position of the blade carrier 17 and deflecting finger 14, various conditions can be arrived at to meet particular conditions.

The operation of the cutter is obvious. If the thread passing from reel 7 to spool 5 over guide 9 contains an enlargement such as the slub *x*, the latter engages the edge of the blade and swings it toward the fixed guide bar 9, against which the thread is pinched and cut. When the slub has been removed and the ends of the thread properly joined by the attendant, the thread is again

passed over the guide bar 9 beneath the deflecting finger 14 and knife 20 (the latter having resumed its normal position by gravity) and the spooling operation is resumed.

5 Should it be necessary to clean or replace the blade 20 it may be readily removed from its carrier 17 by merely freeing the leg 23 of the spring catch 24 and shifting it out of obstructing position. The blade may be 10 then removed and cleaned and the guide bar 9 wiped to remove any deposits thereon which interfere with the free travel of the thread. No disturbance of the adjusted parts is necessary, either for the removal or 15 replacement of the blade.

The adjustability of the clamp longitudinally with respect to the supporting arm 11, the angular adjustability of the deflecting finger 14, the blade carrier 17, and the 20 clamping bracket 8 with respect to the thread guide bar 9, and with respect to each other, renders the attachment readily adaptable to various locations and conditions, and makes possible a very fine adjustment of 25 the parts so that the device may be used to advantage for detecting imperfections in such fine threads as silk, artificial silk fiber, etc. The ready demountability of the blade by an operation which disturbs none of the 30 adjustments—not even of the blade carrier—makes it easy to keep the cutter parts free from gumming, etc., and permits replacement of the cutter blade with only a few seconds interruption of the winding operation. The freely swinging blade is very 35 sensitively responsive and swings into active position on very light stress. The structure as a whole is economically manufactured and is readily adapted, not only to various 40 locations but for use with threads of different denier.

Various modifications of structure will readily occur to those skilled in the art, which attain the advantages of the construction without departing from what I claim as 45 my invention.

I claim:—

1. In a slub cutter, a support, a blade carrier adjustably mounted therein and 50 recessed to afford a segmental V-slot, and a cutter blade mounted in said slot with freedom to swing thereacross, the edge of the blade projecting beyond the carrier.

2. In a slub cutter, a blade carrier bar recessed to afford a segmental V-slot, a cutter 55 blade accommodated in said slot, and a blade latch having an engaging member extending transversely of the V-slot.

3. In a slub cutter, a blade carrier bar recessed to afford a segmental V-slot, a cutter 60 blade accommodated in said slot, a readily displaceable blade support mounted on the carrier and extending across one end of the V-slot for engagement with the blade end, and a cooperating stationary support for the 65 opposite end of the blade.

4. In a slub cutter, a blade carrier bar recessed to afford a segmental V-slot, a cutter 70 blade accommodated in said slot, and a blade-detaining member comprising a pair of parallel legs intersecting the V-slot and engaging the opposite ends of the blade.

5. In a slub cutter, a blade carrier bar recessed to afford a segmental V-slot, a cutter 75 blade accommodated in said slot, and a blade-detaining member comprising a pair of parallel legs intersecting the V-slot and engaging the opposite ends of the blade, one of said legs being readily displaceable to 80 permit removal of the blade without disturbance of the carrier.

6. In a slub cutter, a support, a thread 85 guide mounted thereon, a clamp head adjustably secured on the thread guide, a blade carrier adjustably secured to the clamp head, and a cutter blade mounted for ready detachability on said carrier and adapted for cooperation with the thread guide, together with a deflecting finger adjustably mounted on the thread guide and independent of the 90 clamp head, said deflecting finger governing the angle of approach of the thread to the guide in the neighborhood of the cutter blade.

7. In a slub cutter, a support, a thread 95 guide adjustably mounted with respect to said support, a blade carrier adjustable with respect to said support and with respect to the thread guide, together with a deflecting finger adjustable both with respect to the 100 thread guide and with respect to the blade carrier, said parts forming a unitary attachment.

In testimony whereof I have signed my name to this specification.

DONALD A. MCKENZIE.
